UNITED STATES PATENT OFFICE.

SIMEON T. BROW, OF CHICAGO, ILLINOIS.

DESIGN FOR A NECK-SCARF.

SPECIFICATION forming part of Design No. 11,973, dated October 5, 1880.

Application filed July 10, 1880. Term of patent 3½ years.

To all whom it may concern:

Be it known that I, SIMEON T. BROW, a citizen of the United States, residing at Chicago, in the county of Cook and State of Illinois, have invented and produced a new and original Design for a Gentleman's Neck-Scarf, of which the following is a specification, reference being had to the accompanying drawing, forming part thereof, which drawing is a front view of my newly-designed scarf, this view being deemed necessary to fully illustrate my design.

The leading feature of my design consists in two small lapels, *a a*, attached to the front of the scarf, as represented in the drawing. 15

I claim—

The design of a gentleman's neck-scarf herein shown and described, the same consisting of two small lapels, *a a*, on front of and attached to the scarf.

SIMEON T. BROW.
